DECK OF EDUCATIONAL CARDS FOR LEARNING MORSE CODE

Clifford Maxwell, 304 E. Unaka Ave.,
Johnson City, Tenn.

Filed May 13, 1963, Ser. No. 74,856

Term of patent 14 years

(Cl. D34—13)

FIG. 1

FIG. 2

FIG. 3

FIGURE 1 is a face view for A through N of the alphabet of a deck of educational cards for learning Morse code showing my new design.

FIGURE 2 is a face view of the cards for O through Z of the alphabet, and

FIGURE 3 is a view of the opposite face of one of the cards.

The dominant features of my design reside in the portions shown in full lines.

I claim:

The ornamental design for a deck of educational cards for learning Morse code, as shown and described.
